UNITED STATES PATENT OFFICE.

FRANK H. DAVIS, OF FLORAL PARK, AND CHARLES SCHUMACHER, OF BROOKLYN,
NEW YORK.

ART OR METHOD OF GOLD-LEAFING SURFACES.

1,124,869.

Specification of Letters Patent.

Patented Jan. 12, 1915.

Application filed July 18, 1913. Serial No. 779,882.

To all whom it may concern:

Be it known that we, FRANK H. DAVIS and CHARLES SCHUMACHER, citizens of the United States, residing at Floral Park, 5 Long Island, New York, and 1295 St. Marks avenue, Brooklyn, New York, respectively, in the counties of Nassau and Kings and State of New York, have invented new and useful Improvements in Arts or 10 Methods of Gold-Leafing Surfaces, of which the following is a specification.

This invention relates to the art or method of gold leafing leather, paper, cloth and other surfaces.

15 In the ordinary process of employing and applying gold leaf to surfaces of the character described, the leather, paper, cloth or other material is first printed or stamped with the matter which is to be gold leafed, 20 the roll of gold leaf put into a holder and passed over the impression to apply the gold thereto, the leafed surface then oiled and put back in the press, and the compressed surface stamped again to firmly 25 apply the gold leaf. This is necessary in the ordinary manner of putting up gold leaf for use, wherein the leaf is put up in roll form with a ribbon or tape of paper or other protective material since the loose leaf 30 must be firmly impressed and caused to adhere to the surface.

The object of this invention is to provide a novel mode of gold leafing, whereby surfaces of the character described may be 35 gold leafed at less time and labor and without the waste of material experienced in ordinary processes.

In the accompanying drawing, Figure 1 is a perspective view of a section of gold 40 leaf ribbon used in our improved method. Fig. 2 is a view showing the face of the ribbon as it appears after an impression has been made. Fig. 3 is a view showing the mode of carrying the process into practice.

45 In carrying our invention into practice, we provide a ribbon leaf 1, wound in roll form without the use of the ordinary wooden core, but which may be put up in any other suitable manner for use. This ribbon leaf 50 comprises a strip 2 of paper or other suitable material having upon one of its faces a coating 3 of leaf gold combined with oil and a suitable size, whereby the leaf is caused to adhere to the ribbon strip 2, 55 against any possibility of being blown away

and lost or wasted. The particles of the leaf are bound together by the size and oil in such manner as to form a thin, uniform layer of the gold leaf over the surface of the carrying strip 2, which coating is capable of being transferred to the surface to be ornamented by stamping or making an impression through the ribbon strip, whereby the gold leaf from the ribbon surface is transferred to the leather, cloth or other 60 surface to be ornamented and the latter simultaneously stamped or impressed with the desired matter. Owing to the fact that the particles of the film of gold are held intact by the size and oil, a cleanly transfer 65 from the strip 2 to the surface to be ornamented is effected in accordance with the lines of the impression, leaving any surplus amount of the leaf intact, upon the carrier strip for further use or recovery, thus 70 avoiding all liability of loss from waste.

75 Preferably in the process of using the ribbon leaf, the leather, cloth or paper A is put in the press against a platen or backing surface B, and the strip of gold leaf, while 80 suitably held in position, is disposed between the same and the impression die, stamp or type C, whereby in the operation of the stamp, which comes in contact with the ribbon leaf an impression is made 85 through the leaf into the cloth, paper or leather and the gold transferred to the latter named surface in accordance with the impression and simultaneously with the production of the same.

90 In practice the size and oil are preferably of such a character as to require the use of hot dies or stamps, the heat from which will render the sizing sufficiently fluid or plastic for the transfer, by which greater security 95 against the loss of gold is secured and a more efficient gold impression obtained since the action of the heat of the die on the size and oil tends to gloss or burnish the transferred gold. By this method of operation, the steps of twice stamping and finally oiling the transferred gold, as in the ordinary processes, is avoided, and waste of the gold leaf effectually prevented or reduced to the minimum.

100 Having thus described our invention, we claim:

105 The herein described process of applying gold leaf to the surface to be decorated consisting of affixing the gold leaf to a sup- 110

porting sheet by means of a fusible unctuous adherent and a fusible adhesive size, placing said sheet and gold leaf over the surface to be decorated with the gold leaf next such 5 surface and subjecting said sheet and said gold leaf to the stamping pressure of a heated die, whereby said adherent and size are fused to separate the leaf from the supporting sheet solely along the lines of pres-

sure and to fix the separated leaf to the sur- 10 face against which it is impressed.

In testimony whereof we affix our signatures in presence of two witnesses.

FRANK H. DAVIS.

CHARLES SCHUMACHER.
